C. WILHJELM

SAFETY TEMPERATURE CONTROL

Filed Sept. 18, 1922

Christian Wilhjelm Inventor
By his Attorney
Ivan E. A. Koenigberg

UNITED STATES PATENT OFFICE.

CHRISTIAN WILHEJELM, OF PHILADELPHIA, PENNSYLVANIA.

SAFETY TEMPERATURE CONTROL.

Application filed September 18, 1922. Serial No. 588,930.

To all whom it may concern:

Be it known that I, CHRISTIAN WILHEJELM, a citizen of Denmark, and resident of Philadelphia, in the county of Philadelphia and State of Pennsylvania, have invented certain new and useful Improvements in Safety Temperature Controls; of which the following is a specification.

This invention relates to automatic temperature alarms usable in connection with ovens, boilers, distilling apparatus and other places, where it is desirable that an audible or visible signal or alarm be given when the temperature employed exceeds a predetermined maximum degree.

The object of the invention is to provide an improved automatic temperature alarm adapted for the purposes set forth, and arranged for both portable and permanent installation and use.

In the drawing accompanying this specification and illustrating the invention,

Figure 1 is a view of the device, showing it partly in section and partly in elevation, together with a diagrammatic illustration of the electric circuit used with the device.

Figure 2 is a diagrammatic illustration of a multiple installation of the device.

Referring to the drawing, the device itself consists of a fuse or wire 1, the melting point of which is known, and which is enclosed in a gas tight tube 2 of porcelain, glass, quartz or similar material. The fuse 1 is secured by wires as 3, 3 to suitable outside terminals 4, 4.

The numeral 5 denotes a conductor of suitable material having a melting point higher than the fuse 1. Said conductor may be in the form of a wire or rod having an arm 6 adapted to receive and make contact with the one fuse terminal 4.

The conductor 5 is contained within a tube 7 of suitable insulating material. Outside the latter is mounted a tubular conductor 8 provided with a collar 9. A handle 10, which may be of wood or other suitable material, serves as a handle for the entire device, and the aforesaid parts are secured together by a nut 11 screwed on the end of the conductor 5.

The other end of the fuse holder 2 is held by a lug 12 of a collar 13 which slides on and thus electrically contacts with the tubular conductor 8 being secured thereon by a set screw 14.

Thus it will be seen that the fuse holder

2 is removably held or mounted between and in electrical contact with the two main conductors 5 and 8.

The numeral 15 denotes an alarm or signal box containing an actuating circuit comprising a relay 16 connected in series with a battery 17 and the conductors 5 and 8, and the fuse 1. This circuit is normally closed, so that the armature 18 of the relay remains in attracted or raised position.

The box 15 further contains a normally open signal circuit comprising a signal 19 and a battery 20 and open contacts 21, 21 adapted to be closed by a bridge contact 22 70 aforesaid.

Preferably flexible wires 23 serve to connect the alarm device with the signal box.

The oven or apparatus, the temperature of which is to be signalled, is provided with a suitable opening for inserting the device in the proper position. So long as the temperature is below the melting point of the fuse 1, nothing happens. But when the temperature reaches the melting point of the fuse, the latter will melt, the actuating circuit will be broken, hence the armature 18 will drop and the contact 22 will close the signal circuit and a signal will be given.

A new fuse may then be readily inserted by sliding the collar 13 upon the tube 8, removing the old fuse holder and inserting a new one. The collar 13 provides a means for adjustably securing the fuse holder in electric contact with the actuating circuit.

Figure 2 illustrates a plurality of signal boxes 25 which may have visible signalling devices 26. Each box is connected to its separate fuse device 27, constructed like the one described above. Thus, the signal boxes 95 may be mounted in one place for collective inspection, while the fuse devices may be carried about and employed where required.

The device is simple to manufacture, handy to use and operate and effective for its purpose.

It will be understood that the invention is susceptible of changes in the detailed construction without departing from the spirit of the invention or the scope of the appended claim.

I claim:—

A device of the character described comprising a tool consisting of a relatively long tube of insulating material, an electrically conducting rod within the same having one end projecting beyond the end of said tube

and bent at an angle thereto, a sleeve of electrically conducting material surrounding said tube, a ring of electrically conducting material slidably mounted on said sleeve, 5 means for securing and adjusting the said ring on the said sleeve, said ring having a lug extending to one side thereof, a fuse element

held between the bent end of the said rod and the said lug, a handle for said tool, and means for connecting said conducting rod 10 and the said conducting sleeve to the terminals of an electric circuit.

CHRISTIAN WILHJELM.
